ATTORNEY.

UNITED STATES PATENT OFFICE.

GEORGE CHECKLEY, OF NEW YORK, N. Y.

PROPELLER.

Application filed February 12, 1925. Serial No. 8,774.

This invention relates to propellers and has for its object to increase the efficiency of high speed propellers, such as employed on steamers, warships and motor boats, generally.

In the present type of propellers, it is well known that the greatest power obtained by the propeller occurs at the ends of the blades or in other words, furthest removed from the propeller shaft. The surface of the propeller blade immediately adjacent the shaft operates in a dead center and practically no power is generated from this surface. It is also well known that a suction vacuum exists on the shaft and propeller blade surface, due to the fact that the propeller is moved through the water with a degree of speed greater than the motion of the water, resulting from its gravity or from its endeavor to find a level and the vacuum of course, tends to delay the rearward motion of the blade and retard the action of the propeller. In many instances, however, about one-half of the propeller blade is actually in contact with the water when the propeller is operating at a high rate of speed and consequently it will be recognized that if a greater surface of the propeller blades is presented to the water, more power will be obtained.

Various means have been resorted to in the past to overcome the objects such as by breaking up the vacuum that exists in front and in back of the propeller blades and shaft, by making a hollow propeller blade and by shunting the water in different directions toward the end of the shaft so as to break up the existing vacuum.

My invention, relates to overcoming this problem by utilizing an auxiliary propeller, preferably in front of the main propeller in such manner that the water will be churned or directed immediately against the propeller blades at a point adjacent the inner ends thereof, or in other words, in and about the propeller shaft. It will be thus seen that the maximum surface of the main propeller blades are utilized with the result that greater efficiency is obtained and more power generated. In actual practice, I have found that the auxiliary propeller should be at least about one-half the size of the main propeller and located at a distance sufficiently close to the same without interfering with the operation of the blades so that the water will be directed toward the entire sur-

face of the blades and throughout their entire length.

In order to more fully understand and appreciate my invention, reference is had to the accompanying drawings, showing a preferred embodiment thereof, wherein:

Figure 1 is a front view of the main and auxiliary propellers, the propeller shaft being shown in section.

Figure 2 is a side view.

Referring now to the drawings, wherein like reference characters designate corresponding parts throughout the several views, I have shown a propeller consisting of three blades, although I do not desire to be limited or restricted to the exact number of blades because two, four or five blades may be utilized, if so desired. In the form of the invention shown, 5 designates the propeller shaft and 6 a sleeve keyed thereto and secured on the end of the shaft by any suitable means such as a lock nut 7 and nut 8 as clearly shown by Figure 2 of the drawings. The blades 9 of the main propeller may be of any desired shape and size, being preferably disposed at an acute pitch. Forwardly of the main propeller blades 9, the auxiliary propeller 10 is mounted, being spaced from the main propeller blades 9 so that they may operate together without interference, the propeller 10 assisting and aiding the operation of the main propeller by churning the water which would otherwise engage the surface of the main propeller at a point adjacent the surface of the shaft 5.

The location of the propeller 10 breaks up what might be regarded as the stream line of the water over that surface of the shaft and main propeller, which is a dead volume of water if the main propeller were operating under ordinary circumstances. The blades 10 of the auxiliary propeller drive the water against the entire surface of the blades of the main propeller and since the total surface of the blades are utilized, greater power results. In this manner, the engines or the power driven mechanism generate the greatest amount of power possible, which is otherwise lost because of the lack of resistance on that part of the propeller immediately adjacent the shaft. As shown, the auxiliary propeller is substantially one-half the size of the main propeller and is so spaced therefrom that the effect of the vacuum which ordinarily occurs at the surface of the shaft,

- is thus broken up. Of course, the invention is further carried forth by mounting another propeller in front of the auxiliary propeller 10, and one smaller in size, and in some instances, an auxiliary propeller may be mounted rearwardly of the main propeller. The main and auxiliary propellers may be cast with the sleeve 6 and mounted on the propeller shaft in the usual manner.
- From the above description and objects set forth, a propeller constructed in accordance with my invention will develop greater speed, produce the maximum efficiency from the engine in that an increased surface or resistance of the water is had or in other words, a greater volume of water is agitated with the result that the maximum power obtainable is secured. The power generated for driving the shaft depends, of course, on the propeller surface and the results of the increased surface tends to greater efficiency.

Having shown and described my inven-

tion, what I claim as new and desire to secure by United States Letters Patent is:

1. A propeller shaft, a sleeve keyed to the shaft, a main propeller carried by said sleeve, an auxiliary propeller carried by said sleeve located in front of the main propeller and substantially one-half the size of the main propeller, and the blades of the auxiliary propeller being in alignment with those of the main propeller.

2. A propeller shaft, a sleeve keyed to the shaft, a main propeller and an auxiliary propeller located immediately in front of the main propeller but spaced therefrom, both of said propellers being formed integral with said sleeve, and said auxiliary propeller being substantially one-half the size of the main propeller whereby the volume of water may be agitated by the entire surface of the main propeller.

In testimony whereof I affix my signature.

GEORGE CHECKLEY. [L. S.]
